[57] CLAIM

The ornamental design for a clothing item with pockets for receiving therapeutic packs, as shown and described.

DESCRIPTION

FIG. 1 is a perspective view of a clothing item with pockets for receiving therapeutic packs showing my new design in an open condition;

FIG. 2 is a perspective view thereof in a closed condition;

FIG. 3 is a top plan view thereof;

FIG. 4 is a bottom plan view thereof;

FIG. 5 is a rear elevational view thereof;

FIG. 6 is a side elevational view thereof in a flat condition, the other side being a mirror image thereof; and,

FIG. 7 is a rear elevational view of FIG. 6.

The broken lines in the Figures are for illustrative purposes only and forms no part of the claimed design.

The partial rendering of surfaces is for ease of illustration. It is understood that the partial rendering continues throughout the entire surface on which it is only partially shown.
